UNITED STATES PATENT OFFICE.

CHARLES P. STEINMETZ, OF SCHENECTADY, NEW YORK, ASSIGNOR TO GENERAL ELECTRIC COMPANY, A CORPORATION OF NEW YORK.

REACTIVE COIL.

No. 883,919.

Specification of Letters Patent.

Patented April 7, 1908.

Application filed May 19, 1906. Serial No. 317,748.

To all whom it may concern:

Be it known that I, CHARLES P. STEINMETZ, a citizen of the United States, residing at Schenectady, county of Schenectady, State of New York, have invented certain new and useful Improvements in Reactive Coils, of which the following is a specification.

This invention relates to a mode of controlling the discharge of reactive coils, and 10 more especially those used with mercury vapor rectifiers.

If a reactive coil is energized by a current, say a direct current, and then the circuit is broken, the current in the reactive coil will 15 fall off in an exponential curve which varies with the reactance and the resistance of the circuit. The voltage induced by the reactive coil will follow the same curve. The induced current is at a maximum at the beginning, and dies out gradually. In order 20 to hold the current over for a period of any length, an extremely high reactance is necessary. In many cases, however, and especially in mercury arc lamps or rectifiers 25 for alternating currents, it is desirable to use a reactive coil of as small dimensions as possible and having the least possible amount of reactance, but yet obtain a discharge curve extending over a long period of time. It is 30 not necessary that the current should be high in the beginning of the discharge, but on the contrary it is desirable that the rate of drop should be small, so that during the end of the discharge, when the next half 35 wave is to be started, a considerable current will still be flowing and maintaining proper excitation of the mercury arc device.

I have discovered that by combining with the reactive coil a short-circuited secondary 40 coil of fairly good mutual inductance with the main or reactive coil, but still having some self-inductive reactance against the main coil—that is, so that there is some stray field between the main and secondary coils—45 the discharge curve of the main coil is entirely changed. Since the same number of lines of magnetic force cut the primary coil during the discharge when the secondary coil is used as when it is absent, the total 50 electromotive force induced in the primary or main coil, and consequently the total primary current, is the same in both cases. But the mutual reactance of the two coils causes a lowering of the primary current

during the first part of the discharge and 55 tends to equalize it over a longer period.

In the accompanying drawing, Figure 1 is a diagrammatic representation of a mercury arc rectifier equipped with my improved reactance coils; Fig. 2 is a diagram of the co- 60 ordinated curve of induced current when no secondary coil is used; and Fig. 3 is a diagram showing the effect of the secondary coil.

The alternating current mains 1, 2, are 65 connected with the two anodes 3, 4 projecting into the envelop 5 in which the mercury arc is maintained. The two reactance coils 6, 7 are connected in series across said mains, and the direct current conductor and load 8 are connected from a point between them to 70 the cathode 9. Surrounding each reactance coil is a closed secondary coil 10, 11. The drawing is merely an illustration of one mode of utilizing the invention. It is to be understood that reactances of the special type 75 described may be introduced in the anode leads or in the load circuit in the same way and for the same purpose that simple reactive coils have heretofore been used.

When the source of electromotive force is 80 withdrawn from a simple reactive coil, either by breaking a direct current or by the subsidence of the wave of an alternating current, the voltage and current thereupon induced falls off from the initial value, at first 85 somewhat rapidly and then more slowly, in an exponential curve 12, Fig. 2; the controlling elements being the reactance and the resistance of the circuit. But when the closed secondary coil is added, the primary 90 current at first falls off very rapidly, at a rate approximately corresponding to the self-inductive reactance of the stray field between the primary coil and the secondary coil. At the same time, there appears in the 95 secondary coil a current which rises at first very rapidly, and then more slowly, reaches a maximum, and then gradually drops. As soon as this rise of current in the secondary coil slows up and ceases, the fall of the primary current also becomes less rapid and ultimately very slow so that the primary current is maintained over a period much greater than is the case without the secondary coil. This interaction of the two coils is shown in 105 Fig. 3, where the curve 13 represents the rise and fall of the secondary current, and the curve 14 represents the changed primary

current due to the retarding of the drop in voltage by reason of the cōunteraction of the secondary coil.

What I claim as new and desire to secure by Letters Patent of the United States, is,—

- 5 1. The combination with a vapor electric device, of reactive means connected thereto, and means for retarding the drop of current in said reactive means.
- 10 2. The combination with a vapor electric device, of a reactive coil, and means for maintaining over a long period the inductive discharge of said reactive coil.
- 15 3. The combination with a vapor electric device, of a reactive coil, and means for equalizing the discharge of said coil.
- 20 4. The combination with a vapor electric device, of a reactive coil for maintaining said device active, and a secondary coil in inductive relation to said reactive coil.
- 25 5. The combination with a vapor electric

device, of a reactive coil, and a closed secondary coil in inductive relation to said reactive coil.

6. The combination with a vapor electric 25 device having a plurality of anodes and a cathode, of reactive coils connected to said anodes, and closed secondary coils in inductive relation to said reactive coils to prolong the period of discharge of said reactive coils. 30

7. The combination of a vapor electric device, reactive means for maintaining current flow in said device, and a closed secondary in inductive relation therewith to prolong the discharge of energy from said reactive means. 35

In witness whereof, I have hereunto set my hand this 18th day of May, 1906.

CHARLES P. STEINMETZ.
